UNITED STATES PATENT OFFICE.

GEORGE J. WINKLE, OF SENECA FALLS, NEW YORK.

TOOL-HOLDER FOR TURRET-MACHINES.

SPECIFICATION forming part of Letters Patent No. 664,344, dated December 18, 1900.

Application filed October 31, 1899. Serial No. 735,389. No model.

To all whom it may concern:

Be it known that I, GEORGE J. WINKLE, a citizen of the United States, residing at Seneca Falls, in the county of Seneca and State of New York, have invented a new and useful Tool-Holder for Turret-Machines, of which the following is a specification.

My invention relates to improvements in tool-holders for turret-machines designed for turning bolts, studs, pins, screws, and other kinds of work; and one object in view is to provide an improved tool-holder by which the tool may be given a compound adjustment, first, to position the tool in operative relation to the work, and, secondly, to advance the tool according to successive cuts on the work.

A further object is to provide means which allows the tool to drop away from the work on the adjustment of the tool-carrier cam in one direction without disturbing the operative relation of the tool-carrier pivot to the work.

A further object is to provide improved means for holding the tool-holder in proper relation to the work, such holding means being readily adjustable to work which may vary in diameter.

A further object is to provide a tool-holder of simple construction adapted for use in connection with standard types of turrets, as well as to provide for the secure clamping and ready interchange of different tools in the pivotal tool-carrier.

With these ends in view the invention consists in the novel combination of elements and in the construction, arrangement, and adaptation of the various parts for service, which will be hereinafter fully described and claimed.

To enable others to understand the invention, I have illustrated a preferred embodiment thereof in the accompanying drawings, forming a part of this specification, and in which—

Figure 1 is a side elevation, partly broken away and in section, of a tool-holder constructed in accordance with my invention and illustrating the same in operative relation to a piece of work. Fig. 2 is a sectional elevation on the plane indicated by the dotted line $x-x$ of Fig. 1 looking in the direction indicated by the arrow. Fig. 3 is a detail

plan view of the body of the tool-holder with the pivotal tool-carrier, the means for adjusting the same, and the work-engaging devices removed from said body. Fig. 4 is a side elevation of the tool-carrier removed from the body of the tool-holder. Fig. 5 is an edge elevation of the tool-carrier. Fig. 6 is a detail cross-sectional view on the plane indicated by the dotted line 6-6 of Fig. 2. Fig. 7 is a detail view of the adjustable plate for the work-engaging holder.

The same numerals of reference are used to indicate like and corresponding parts in each of the several figures of the drawings.

The tool-holder of my invention contemplates the employment of a body having a shank or stem adapted to be fitted in any tool-socket of an ordinary turret, a pivotal tool-carrier supported on the body, a compound eccentric or cam-adjusting device carried by the body in operative relation to the tool-carrier, work-engaging plates supported by the body opposite to the tool-carrier, and means for adjusting said plates.

The elements of my improved tool-holder are represented, in the preferred embodiment of the invention, by the accompanying drawings, and I will now proceed to a detailed description of the construction and the mode of operation.

The body of the tool-holder is indicated in its entirety by the numeral 10, the same being cast in a single piece of metal. This body has an open front plate 11, from one end of which is extended an arm 12, having a circular opening 13. The front plate is provided, at the opposite end from the arm, with the parallel guide-flanges 14, which are disposed above and below the opening in said plate and are arranged to extend laterally therefrom, said guide-flanges being provided in their opposing faces with the coincident longitudinal grooves 15. A back plate 16 forms an integral part of the holder, so as to lie parallel with the front plate, said back plate having a shank or stem 17, which is preferably tubular and extends from said plate at right angles to the body.

The tool-carrier 18 is represented as a single block or casting. (Shown more clearly by Figs. 4 and 5.) This tool-carrier is arranged laterally alongside of the front plate 11, and it is pivotally supported on said plate of the

tool-holder body by a pivotal stud 19, which passes through a suitable opening in the lower end of the carrier and is fastened firmly to the front plate 11, at the lower edge thereof. Said 5 tool-carrier has a tool-receiving slot 20 formed in its outer face, said slot 20 having the top and bottom walls indicated at 21 22. In the lower wall 22 is a recess 23, and this lower wall is curved in a direction transverse of the axis 10 of the carrier, the recess 23 corresponding in curvature to the bottom wall 22. A bearing-plate 24, preferably of hardened steel, is fitted snugly on the curved wall 22 of the slot, said plate having a rib 23^a, which enters the recess 23. The bearing-plate has its lower face 15 curved to conform to the recess 23, so that the plate will be keyed to the carrier; but the upper face of this hardened bearing-plate is parallel with the straight top wall 21 in the tool-slot of the carrier. The tool 25 may be 20 of any suitable construction, with parallel side edges, and it is placed in the slot 20 of the carrier so that its bottom edge will rest on the straight upper face of the hardened-steel 25 bearing-plate 24. Clamping-screws 26 are mounted in the upper part of the carrier and in the vertical plane of the slot 20 therein in order that the inner ends of the screws may project into the slot and engage with the top 30 edge of the tool 25, whereby the tool may be clamped firmly upon the bearing-plate in a manner which will hold said tool securely in place on the pivotal carrier. It is evident 35 that the clamping-screws may be released for the purpose of adjusting the tool in the carrier or for removing the tool, so as to permit it to be replaced by another tool.

One element of the compound cam-adjusting device is the eccentric bushing 27. This 40 bushing is provided at one end with an enlarged head or flange 28, and the eccentric part of said bushing is fitted loosely in the circular opening 13 in the arm 12 of the tool-holder front plate, so that one end of the eccentric bushing 27 will lie flush with the front 45 face of the arm 12, while the head or flange of said bushing will bear against the rear face of the arm, as clearly shown by Fig. 2. The head or flange 28 of the eccentric bushing has 50 a series of radial sockets 29, in either of which may be fitted an adjusting-pin 30, said pin serving as a means for conveniently turning the eccentric bushing on its axis within the circular opening of the arm forming a part of 55 the tool-holder body, whereby the position of the eccentric bushing with relation to the tool-carrier may be varied. Another element of the compound cam-adjusting device is the cam-shaft 31, which is loosely journaled in 60 the eccentric bushing. This cam-shaft carries a cam 32, having a continuous working face of different radii, said cam being fast or integral with one end of the shaft in order to turn therewith. The cam-shaft is inserted 65 in the bushing in a manner for the cam 32 therein to bear against one end of the bushing and the front face of the arm 12, so that

the cam 32 is in operative relation to an edge of the pivotal tool-carrier, and to the free end of the cam-shaft is pinned or otherwise detachably secured a handle or lever 33, the latter serving as the means by which the cam-shaft may be turned in the bushing for the purpose of changing the position of the cam 32 with relation to the pivotal tool-carrier. Said tool-carrier is provided in the edge which faces the cam-shaft with a longitudinal recess 34, into which projects one edge of the cam 32, (see Figs. 1 and 5,) the parts being thus disposed to maintain the cam in operative relation to the pivotal carrier.

The cam-shaft and the cam thereon are designed to be turned freely relative to the eccentric bushing for the purpose of easily and quickly adjusting the tool-carrier to or from the work; but the bushing itself is also designed to be adjusted by the pin 30 in order to preliminarily position the cam and its shaft and move the same bodily inward and outward relative to the work, thus giving an increased range of throw to the cam-adjusting devices for the pivotal carrier and making the improved tool-holder readily applicable to different pieces of work which vary in diameter. Ordinarily, however, the eccentric bushing remains at rest, and I have provided means by which the eccentric bushing may be frictionally confined in position for the purpose of preventing the bushing from partaking of the free play of the cam and its shaft. Such confining means for the bushing is represented as a frictional brake device embodied in the form of a block or disk of some suitable compressible material 36, such as rawhide or leather, and a compression-screw 37. The friction-block and its compression-screw are housed within a threaded opening or socket 35, which is formed radially in the arm 12. The friction block or disk is placed in the bottom of the socket 35 or opening, so as to bear directly upon the eccentric bushing, while the compression-screw has threaded engagement with the wall of the socket in order that it may be adjusted therein to force the friction-block into firm engagement with the bushing. It is evident 105 that the screw may be adjusted to force the friction-block tightly into engagement with the bushing for holding the latter firmly in place; but the bushing may be turned by pressure applied to the adjusting-pin 30, the pressure so applied being sufficient to overcome the frictional engagement of the friction brake-block and said bushing.

38 39 indicate the work-engaging blocks, 125 which are fitted between the parallel guide-flanges 14 on the front plate of the tool-holder body. These blocks or plates are arranged in lateral contact, and at their edges said blocks have the guide-ribs 39 fitted slidably 130 in the grooves 15 of said guide-flanges. The blocks or plates are thus slidably connected with the flanges for adjustment toward or from the work, and at their inner ends said

blocks have the oppositely-inclined faces 40, adapted to be presented so as to partially embrace the surface of the work. An adjusting-strap 41 lies across the outer ends of the plates 5 or blocks 38 and the holder-body. Said strap has a transverse opening in one end and a notch or open-ended slot in the other end. Adjusting-bolts 42 are screwed into the guide-flanges 14 on opposite sides of the blocks or 10 plates 38, and one of said bolts passes through the opening of the strap, while the other bolt passes through the notch in the other end of the strap. It is evident that the bolts may be turned to press the strap against the end 15 of the plates or blocks to force the beveled faces thereof into engagement with the work; but to release and remove the blocks the screws are reversed and the strap is turned on one screw or bolt to withdraw its notched 20 or slotted end from the other screw or bolt, thus adjusting the strap out of alinement with the plates or blocks and permitting their ready removal from the tool-holder body.

The operation may be described briefly as 25 follows: The tool-holder having been supplied with the proper tool and its shank or stem fitted in one of the tool-sockets of an ordinary turret, the work is passed through the body of the holder, and the bolts 42 are ad-30 justed to make the blocks or plates 38 engage with one side of the work. The eccentric bushing is now adjusted to preliminarily move the cam and the pivotal carrier into po-35 sition for the tool to lie close to the work, and finally the handle or lever is manipulated to turn the cam-shaft in the bushing and also turn the cam for that part of its working face of greater radius to lie opposite the tool-car-40 rier. This adjustment of the cam causes it to impinge against the edge of the carrier and move the latter and the tool for the said tool 45 to engage the work. It is evident that the cam-shaft and cam may be adjusted to suc-cessively advance the tool, but by reversing the cam-shaft the cam is turned for its part of less radius to engage the tool-carrier, and thus permit the latter to drop away from the work.

One of the important features of my inven-50 tion consists in locating the pivotal stud of the tool-carrier at a point almost below the position assumed by the work in the body of the tool-holder, so that the tool-carrier in its working position will be inclined to the hori-zontal axis of the cam-shaft. This inclined 55 position of the tool-carrier causes it to rest by gravity against the cam, and any adjustment

of the cam will be instantly followed or re-sponded to by a movement of the pivotal in-60 clined tool-carrier. It is therefore evident that the tool-carrier will drop away from the work by gravity and that it is held to its working position by the pressure of the cam thereon.

Changes may be made in the form and pro-65 portion of some of the parts while their es-sential features are retained and the spirit of the invention embodied. Hence I do not de-sire to be limited to the precise form of all 70 the parts as shown, reserving the right to vary therefrom.

Having thus described the invention, what I claim is—

1. In a tool-holder for turret-machines, the combination with a movable tool-carrier, of 75 a compound cam-adjusting device composed of two independent cams or eccentrics and capable of two successive and independent periods of operation to preliminarily position the tool-carrier and to successively advance 80 the latter to the work, substantially as de-scribed.

2. In a tool-holder for turret-machines, the combination with a movable tool-carrier, of 85 a shiftable eccentric-support, a cam mounted in the eccentric-support to be shiftable therewith and engaging with the tool-carrier, and means for individually adjusting the shift-able eccentric-support and the cam, substan-tially as described. 90

3. In a tool-holder for turret-machines, the combination with a movable tool-carrier, of 95 a shiftable eccentric-support, an adjusting-cam mounted in the eccentric-support to be shiftable therewith, a friction-brake engag-ing with the eccentric-support to restrain the latter from play with the cam, and means for adjusting the cam separately from the eccen-tric-support, substantially as described.

4. In a tool-holder for turret-machines, the 100 combination with a movable tool-carrier, of an eccentric bushing having a yieldable clamping device associated therewith, a cam-shaft mounted in said bushing and provided with an operating-handle, and a cam fast with 105 the shaft and engaging with the tool-carrier, substantially as described.

In testimony that I claim the foregoing as my own I have hereto affixed my signature in the presence of two witnesses.

GEORGE J. WINKLE.
